(57) **CLAIM**

The ornamental design for an automotive hood, as shown and described.

DESCRIPTION

FIG. 1 is a front end/right side perspective view of a first embodiment automotive hood in accordance with the present invention, wherein a front end/left side perspective view of the automotive hood is a mirror image thereof;

FIG. 2 is a top/right side perspective view of the automotive hood of FIG. 1;

FIG. 3 is a front end perspective view of the automotive hood of FIG. 1;

FIG. 4 is a front end/right side perspective view of a second embodiment automotive hood in accordance with the present invention, wherein a front end/left side perspective view is a mirror image thereof;

FIG. 5 is a top/right side perspective view of the automotive hood of FIG. 4; and,

FIG. 6 is a front end perspective view of the automotive hood of FIG. 4.

The broken lines are for illustrative purposes only and form no part of the claimed design.
